VOLTAGE INDICATING DEVICE

Ted E. Foulke, Nutley, N. J., assignor to General
Electric Vapor Lamp Company, Hoboken, N. J.,
a corporation of New Jersey

Application October 15, 1935, Serial No. 45,128

2 Claims. (CL. 175—183)

The present invention relates to voltage indicating devices and particularly to the use of electric gaseous discharge devices to indicate potential differences.

5 A particular object of the invention is to provide a simple and sturdy device which will indicate by the length of a line of light the approximate relative potential of an electrical conductor to ground or another conductor. A further object of the invention is to provide a device of this 10 type using a plurality of gaseous electric discharge devices to produce the line of light. Still other objects and advantages of the invention will appear from the following detailed specification 15 or from an inspection of the accompanying drawing.

The invention consists in the new and novel structure which is hereinafter set forth and claimed.

20 A simple and sturdy voltmeter is often desired for use in testing high voltage circuits. Since such a device must be readily portable it is desirable that it should be both light in weight and devoid of moving parts. It is likewise desirable 25 that such a device should have an extended range, so as to be usable with any of the voltages commonly encountered. In addition it must be reasonably accurate and above all certain in its indication, especially where high voltage circuits are 30 being tested, since failure of the device might easily lead to the death of a lineman through touching what appeared to be a dead wire. At the same time it is essential that the device should be relatively inexpensive.

35 I have now discovered that all of these requirements are fully met by the novel use of a plurality of electric gaseous discharge devices connected across a potentiometer in a unique manner. With this novel structure the breakdown potential of 40 these devices is utilized to measure the applied potential, more of the lamps lighting with higher potentials, the effect being that of a line of light whose length increases as higher potential is applied. Due to this novel use of a plurality of 45 lamps an element of safety is introduced since in every case except where only one lamp is lighted an indication of the approximate voltage is given even though one of the cathode glow lamps has been totally destroyed. Hence there is little opportunity for a live line to be mistaken for a dead one, with perhaps fatal results.

For the purpose of illustrating my invention I have shown a preferred embodiment thereof in the accompanying drawing, in which

55 Fig. 1 is an elevational view of a voltage indi-

cating device intended for use with relatively high voltage circuits.

Fig. 2 is a fragmentary sectional view of the device of Fig. 1 showing the gaseous discharge lamps therein, and

Fig. 3 is a schematic wiring diagram showing the electrical connections to these lamps.

As shown in the drawing my novel voltage measuring device has a housing consisting of a long fiber or other suitable insulating tube 1 with 10 a handle 2 at one end thereof and a conical contact cap 3 at the other end thereof. Said tube 1 has an elongated opening 4 therein beneath which there is positioned a series of cathode glow lamps 5, 6, 7, 8, 9, 10 and 11. As illustrated these 15 lamps are of the type disclosed in my Patent No. 1,965,585, granted July 10, 1934, but it is to be understood that various other types and sizes of these gaseous discharge lamps may be substituted therefor if desired. Said lamps are equally spaced 20 along the opening 4 and are so arranged that their electrodes can be clearly seen through said opening, any suitable supporting means (not shown) being used to retain the lamps in the desired position. Within said tube 1 there is a potentiometer 12 having a resistance of the order of 25 55,000 ohms which is connected in series with a resistance 13 of the order of 1.75 megohms. The free end of said potentiometer is connected to the grounded lead 14 which extends out through 30 a suitable opening in the tube 1, while the free end of the resistance 13 is connected to the contact cap 3. Another resistance 15 is connected in series with a switch 16 across the potentiometer 12, said resistance having a value of the order of 35 53,000 ohms, whereby the voltage drop across said potentiometer is cut in half when said switch is closed, the range of the instrument being thereby doubled.

The lamp 5 is connected in series with a ballast 40 resistance 17 of the order of 450,000 ohms across the entire potentiometer 12, this resistance, as shown, being formed from carbon impregnated paper. With the values given above for the various resistances approximately 60 volts will be 45 impressed across said lamp 5 when a potential difference of 2,000 volts exists between the cap 3 and ground with the switch 16 open, or 4,000 volts with the switch 16 closed. Since this is equal to or slightly above the breakdown potential of 50 the lamp 5 this lamp will light under these conditions. The lamp 6 is in turn connected in series with a somewhat smaller resistance 18 across approximately two-thirds of the potentiometer 12, whereby the voltage on said lamp 6 is sufficient 55

to light it when the applied potential is 3,000 volts. The remaining lamps 7, 8, 9, 10 and 11 are similarly connected across decreasing fractions of the potentiometer 12 in series with impedances 19, 5 20, 21, 22 and 23, respectively. These fractions are so chosen in the present case that successive lamps light up with each increase of a thousand volts, and the tube 1 is calibrated accordingly. The indicated values are, of course, doubled when 10 the switch 16 is closed. The resistances 17 to 23 are preferably graduated in value so that the current taken by each of the lamps 5 to 11 is the same when all the lamps are lighted. Thus the line of light is uniform in intensity throughout 15 its length, but varies in length and in brilliancy with the applied potential.

The opening 4 is closed with a glass 24, which is preferably ruby in color where neon lamps are employed. This glass tends to increase the 20 illusion of a line of light, and likewise due to its color serves to assist in reading the indication in daylight. Where desired, of course, additional screening means, such as a black plate used as a background, may be used to cut down 25 the extraneous light received by the observer from around the lamps, so as to increase the contrast and thus still further facilitate the reading of the instrument.

In the use and operation of this device the 30 lead 14 is connected to ground and the contact cap 3 then applied to the conductor 25 whose potential to ground it is desired to measure. With the switch 16 in the open position the lamps 5 to 11 will light up, provided the potential 35 of the conductor 25 is 2,000 volts or more, in accordance with the potential, the lamp 5 lighting up at approximately 2,000 volts, and one additional lamp lighting for each additional increment of 1,000 volts. When the switch 16 is 40 closed these values are doubled.

With this novel arrangement an element of safety is introduced through the plurality of lamps employed. Thus supposing the lamp 6, for example, should be rendered inoperative for 45 any reason. The lamp 5 would still operate and show that the potential was at least 2,000 volts, while if the potential was 4,000 volts or more there would be merely a dark space in the line of light, the operator thus being instantly notified 50 that the lamp 6 was inoperative, so that there is little opportunity for the operator to mistakenly assume that the conductor 25 is dead, due to failure of the discharge devices.

With the arrangement shown the high voltage 55 is, of course, entirely confined to the end of the tube 1 which is remote from the handle 2, nothing but low voltage being applied to the lamps, while the switch 16 is grounded, so that there is no hazard to the operator in handling 60 and operating the instrument, even on potentials as high as 16,000 volts. Likewise the series resistance 13 is so high that no hazard would exist even if the ground connection 14 should be opened by accident or otherwise.

65 This novel device is extremely light and portable, and is singularly rugged and immune from damage as a result of handling, due to its lack of moving parts. The lamps 5 to 11 are likewise

extremely sturdy and withstand without difficulty exceedingly rough handling, far beyond anything they will normally encounter in this class of service. The device is likewise extremely simple and inexpensive, as compared to the devices now in use for measuring these high potentials. In addition this novel device not only has an unusually large voltage range, but also can tolerate large excess voltages without damage to the device.

While I have described my invention by reference to a particular embodiment thereof which has been found to give exceptionally good results it is to be understood that it is not limited thereto, but that various omissions, substitutions and changes, within the scope of the accompanying claims, may be made in the structure shown and described without departing from the spirit of my invention.

I claim as my invention:—

1. A voltage measuring instrument comprising, in combination, an insulating tube having a contact on one end thereof, a potentiometer within said tube and connected with said contact, a plurality of electric gaseous discharge lamps having a substantially fixed breakdown potential within said tube and connected across different fixed fractions of said potentiometer, said fractions being so graduated that successive lamps light up as a linear function of the voltage drop in said potentiometer, said lamps being located behind a translucent portion of said tube and arranged sequentially whereby the illumination of successive lamps gives the illusion of an increasing line of light, a scale on the face of said tube to calibrate said line of light, and a resistance between each individual lamp and said potentiometer, said resistances being so varied in value that the current through each of said lamps is substantially the same when all of said lamps are operating.

2. A voltage measuring instrument comprising, in combination, an insulating tube having a contact on one end thereof, a potentiometer within said tube and connected with said contact, a plurality of electric gaseous discharge lamps having a substantially fixed breakdown potential within said tube and connected across different fixed fractions of said potentiometer, said fractions being so graduated that successive lamps light up as a linear function of the voltage drop in said potentiometer, said lamps being located behind a translucent portion of said tube and arranged sequentially whereby the illumination of successive lamps gives the illusion of an increasing line of light, a scale on the face of said tube to calibrate said line of light, a resistance between each individual lamp and said potentiometer, said resistances being so varied in value that the current through each of said lamps is substantially the same when all of said lamps are operating, an impedance connected in series with said potentiometer, and means including a switch located in the wall of said tube to shunt said potentiometer at will to change the voltage range of said device.

TED E. FOULKE.
